STROPPER

Joe D. Chiesa, Broadus, Mont.

Application July 21, 1939, Serial No. 285,779

2 Claims. (Cl. 51—280)

Those who have studied the making of razor stroppers are aware that wooden bases for such articles have been known heretofore. Wooden base stroppers, however, have not proven to be entirely satisfactory. The problem presented embraces selecting the stropper surface material, and selecting a wood best adapted to serve as the base or body of a stropper to which the best combination of materials is applied.

10 The foregoing being true, this invention proposes, through the use of red cedar, linseed oil and lampblack, to produce a better stropper than has been brought out heretofore, the characteristics of red cedar being such that when boiled in linseed oil, that wood will furnish the most satisfactory body or base for a stropper. The invention aims, further, to provide a novel process for making a razor stropper.

15 It is within the province of the disclosure to improve generally and to enhance the utility of devices of that type to which the present invention appertains.

20 With the above and other objects in view, which will appear as the description proceeds, the invention resides in the combination and arrangement of parts and in the details of construction hereinafter described and claimed, it being understood that changes in the precise embodiment of the invention herein disclosed, 25 may be made within the scope of what is claimed, without departing from the spirit of the invention.

20 In the accompanying drawing:

Fig. 1 shows, in perspective, a block of red cedar wood, adapted to form part of a device constructed in accordance with the invention;

Fig. 2 is a transverse section of the completed article.

25 A block 1 of red cedar wood is boiled in a siccative oil, preferably linseed oil, until the block is permeated, as indicated at 2, ten minutes of boiling being enough, ordinarily, for a block the size of a razor stropper. The surplus oil is wiped off, and before the oil has dried or set, as much lampblack 3 as the wood will take is worked, under pressure, into the stropping surfaces 4 of the block. The oil dries, and effective stropping areas result.

30 Considering the characteristics of lampblack and linseed oil, and the nature of red cedar wood, nothing can be substituted for that wood with satisfactory consequences.

The article has no appreciable virtue as a hone, 35 but as a stropping device it will edge-up a razor quicker and more perfectly than the ordinary leather or canvas stropper, or a stropper which does not have a red cedar body.

What is claimed is:

1. A razor strop comprising a piece of red cedar the fibers of which retain lampblack and a siccative oil.

2. A method of making a razor strop, which comprises boiling a piece of red cedar in linseed oil, and working lampblack into the piece, under pressure, before the oil has dried.
